UNITED STATES PATENT OFFICE.

PAUL L. CROWE, OF JERSEY CITY, NEW JERSEY.

STOKER MECHANISM.

962,322.

Specification of Letters Patent. Patented June 21, 1910.

Application filed September 24, 1907. Serial No. 394,390.

To all whom it may concern:

Be it known that I, PAUL L. CROWE, a citizen of the United States, residing at Jersey City, in the county of Hudson and State 5 of New Jersey, have invented certain new and useful Improvements in Stoker Mechanism; and I do hereby declare the following to be a full, clear, and exact description of the invention, such as will enable others 10 skilled in the art to which it appertains to make and use the same.

This invention relates to stokers for furnaces and the like, and has for an object to provide a stoker of improved design embodying improved features of economy, both 15 of fuel and labor.

A further object of the invention is to provide in a stoker a frame of improved construction adapted to support a traveling 20 grate mounted thereon.

A further object of the invention is to provide in a device of the class a traveling grate embodying new and improved features, both in the matter of the grate bar 25 and the connection with the traveling members.

A further object of the invention is to provide in a stoker improved means for admitting fuel to the combustion chamber.

30 A further object of the invention is to provide in a stoker an improved form of clean-out door.

A further object of the invention is to provide in a stoker an improved form of 35 radiating arch.

With these and other objects in view, the invention comprises certain novel constructions, combinations and arrangements of parts, as will be hereinafter fully described 40 and claimed.

In the drawings:—Figure 1 is a view of the stoker showing the frame in side elevation with parts broken away to exhibit the internal construction and showing the radiating arch in section. Fig. 2 is a view in end elevation of the stoker as taken along arrow 2 of Fig. 1 with parts broken away to show the internal construction. Fig. 3 is a perspective view of one of the grate 45 bars. Fig. 4 is a perspective view of the end roller over which the traveling grate passes. Fig. 5 is a view in vertical transverse section of a pair of associated grate bars. Fig. 6 is a perspective view of the fuel controlling 50 means. Fig. 7 is a view in side elevation of 55 one of the sprockets over which the travel-

ing grate passes and from which it receives motion. Fig. 8 is a vertical sectional view of one of the improved sprockets taken on line 8 of Fig. 7. Fig. 9 is a fragmentary 60 view of one end of a grate bar showing the shoe means for attachment to the traveling chain. Fig. 10 is a fragmentary view of the ends of the grate bar opposite to that shown at Fig. 9 and showing means for attaching the grate bar to a horizontal link of the chain. 65

Like characters of reference designate corresponding parts throughout the several views.

The improved stoker forming the subject-matter of this application comprises a frame composed of side pieces 15 and 16, preferably composed of bar metal, the latter being disposed beneath the former and inclined 70 relative thereto with the rear or back end of the frame spaced wider than the front end. The frame pieces 15 and 16 are supported and secured together and spaced by means of struts 17 at the rear end of the 75 furnace, and the supporting frame members 18 at the front end of the furnace. It is to be understood that the stoker, of which the frame forms a part, is set within the combustion chamber 19 of a furnace for heating 80 any approved object, as the conventional boiler 20 and the front end of the furnace is closed by means of a plate 21 forming also the front or outer end of the stoker. The frame pieces 15 and 16 are also spaced 85 apart adjacent their forward end by means of a strut 22 and between the frame pieces forming the opposite sides of the stoker is journaled a roller 23 shown at Fig. 4 in perspective by the shaft or trunnions 24, 90 and with a shaft 25 journaled at or adjacent the forward end of the frame and carrying upon opposite ends sprockets 26 shown in detail in Figs. 7 and 8 and over which sprockets chains 27 are moved by rotating 95 the shaft 25. It will be noted that the chain 27 comprises alternating vertical and horizontal links which are maintained in such relative positions by the formation of the sprockets 26 as shown. Transversely between the chains 27 are disposed grate bars 28, each of said bars having at one end a hook 29 proportioned to be inserted through one of the vertical links of the chain 27 and at its opposite end with registering recesses 100 30 proportioned to receive upon opposite sides hooked engaging members 31 adapted.

to hook through and engage one of the horizontal links of the chain 27, as shown at Fig. 10.

The grate bar 28 is provided with a web 32 of such conformation as to conform substantially with the external curvature of the roller 23 so that as the said grate bars 28 carried by the chains 27 pass over the said roller 23, practically all of the air is shut off and is, therefore, obliged to pass through the grates while traveling upon the upper side and the length of the stoker.

Beneath the rearward end of the stoker and beneath the roller 23 an ash space 33 is provided terminating at the bottom in any approved means for discharging the ash as the chute 34. Spaced transversely beneath the frame pieces 16 are a plurality of rollers 35 journaled upon shafts 36 adapted to carry the traveling grate in its return movement and inverted position, and against the rearward one of said rollers 35 a hinged plate 37 is arranged to bear at its upper end to close the passage beneath the stoker and to prevent ash from passing therethrough, also to practically shut off the air from passing beneath the stoker and through the ash space 33 into the combustion chamber 19. The door or plate 37 is pivoted above the center and held in closed position by the weight of its lower part, so that any clinkers or any inequalities may pass through and by the said door, and the said roller 35 is supported upon springs 38 which maintain the said roller in yielding contact with the under side of the traveling grate by which arrangement clinkers may also pass by the said roller as well as the said door without fracturing or straining the structure.

To carry and support the upper or fuel supporting surface of the traveling grate a plurality of rollers 39 are employed journaled upon shafts or trunnions 40, the said shafts and rollers being alined longitudinally of the frame but owing to the fact that the chain 27 comprises alternate horizontal and vertical links, it will be seen that as the said chain passes over the rollers 39, the links will raise portions of the said chain and the grate bars connected with such portions as indicated by the arrows 41 in Fig. 1, so that the movement of the traveling grate is undulatory, keeping the fuel thereupon in a loosened condition and preventing undue coking and concentration of the fuel.

Above the forward end of the traveling grate a hopper 42 is supported in any approved manner as by the frame pieces 18 and in the lower open end of said hopper 60 is journaled a segmental controlling device shown in perspective at Fig. 6 and embodying end plates or disks 43 having trunnions 44 extending in opposite directions axially therefrom and journaled in the end walls of 65 the hopper. Between the disks a segmental

plate 44 is provided proportioned to close the opening 45 in the lower side of the hopper, and a shield or baffle plate 46 is mounted within the hopper having a curved plate 47 proportioned and positioned to permit the segmental plate 44 to pass in the rear thereof and to be protected in such movement thereby and by the baffle plate 46, so that the controlling device may be rotated in the direction indicated by the arrow without the segmental plate 44 engaging with and being stopped by the fuel contained in the hopper. Upon the end of one of the trunnions 44 and without the stoker and furnace structure, a weight 48 is mounted 70 adapted to hold the feeding device normally closed.

Beneath the feed opening 45 a feed plate 49 is pivoted as by the shaft 50 journaled in the stoker or furnace structure and preferably in the frame piece 18 and upon the said shaft 50 a weight 51 is mounted of such proportion and in such manner as to equalize the weight of the feed plate provided also with a handle 52 for convenience of 85 manipulation and with a catch or detent 53 positioned to hold the door normally in closed position. It will be seen that the front plate 21 of the stoker and furnace is curved over the end of the stoker and extended as at 53 beneath the lower edge of 90 the feed plate.

To the rear of the rear wall 55 of the hopper 42 a radiating arch 56 is provided comprising a plurality of sections as indicated in dotted lines in Fig. 2 being formed keyed in the well known manner of arch construction and with bolts 57 disposed between and their heads embedded in adjacent sections and extending through the rear plate 55 of 100 the hopper securing the arch thereto. To further support the arch skewbacks 58 extend outwardly from the inclosing walls of the furnace and provided with inclined surfaces proportioned to engage the extremities 110 of the blocks and support the arch.

The lower edge of the rear wall 55 of the hopper is curved as at 58' to inclose a cooling device shown conventionally at 59.

The grate bars 28 comprise preferably a 115 bar portion supported upon the web 32 and with the fingers of the grate 39 extending only upon one side of the bar portion and normally approximately in engagement with the next adjacent bar and positioned to vary 120 if there is a movement of the chain upon the inclined side of the bar to prevent one bar settling materially below the adjacent bar.

In operation it will be understood that fuel is admitted by rotating the segmental 125 control in the direction indicated by the arrow in Fig. 1 to open thereby the feed opening 45 of the hopper the fuel passing therethrough upon the feed plate 49 and owing to the inclination of such feed plate 130

passes obliquely downward upon the surface of the traveling grate comprising the chain 27 and the grate bars 28. The traveling grate as it passes over the rollers 39 is given 5 an undulatory movement in the manner above described and air is forced into the stoker beneath the grate and fed through the traveling grate in the usual well known manner so that the fuel upon the surface 10 of the traveling grate is consumed as the grate travels from front to rear. It is, of course, designed to move the grate at such a rate that the fuel will be entirely consumed before it reaches the rear end so that 15 nothing but ash is discharged over the rear end of the traveling grate and air is prevented from passing in any great quantities from beneath the stoker through the ash space 33 by reason of the formation of the 20 roller 23 and the interposition of the pivoted plate 37.

The feed plate, as implied by its name, serves not only to direct the flow of fuel from the feed opening 45 to the traveling 25 grate, but also, in case of necessity, to permit access to the interior of the combustion chamber, and to the stoker.

The radiating arch formed as described 30 of the keyed segments is found to be a very important feature of the present invention, especially in connection with the means for supporting such keyed segments comprising the bolts 57 extended through the rear plate or wall of the hopper and also the skew- 35 backs which are rigid or integral with the inclosing wall of the furnace adapted to support the opposite ends of the arch and owing to its keyed structure supporting thereby the entire arch when held in engagement by the bolt.

What I claim is:—

1. The combination with a furnace having a grate surface and ignition arch above the grate surface, of skewbacks mounted at 45 the side of the furnace and extending the depth of the arch, said arch comprising keyed blocks the depth of the arch, all self-

supporting upon and between the skewbacks, a member arranged transversely of the outer face of the arch, and retaining 50 means connecting each of the blocks with such transverse member.

2. The combination with a furnace having a grate surface and an ignition arch above the grate surface, of skewbacks mounted at 55 the sides of the furnace and extending the depth of the arch, said arch comprising keyed blocks the depth of the arch, all self-supporting upon and between the skewbacks and forming a continuous plain under 60 surface throughout the transverse extent of the arch, a member arranged transversely of the outer face of the arch, and retaining means connecting each of the blocks with such transverse member.

3. The combination with a furnace having a grate surface and ignition arch above the grate surface, of skewbacks mounted at the sides of the furnace and extending the depth of the arch, said arch comprising 70 keyed blocks the depth of the arch self-supporting upon and between the skewbacks, a hopper, and bolts secured between adjacent keyed blocks and securing the hopper to the arch.

4. The combination with a furnace having a grate surface and ignition arch above the grate surface, of skewbacks mounted at the sides of the furnace and extending the depth of the arch, said arch comprising keyed 80 blocks the depth of the arch all self-supporting upon and between the skewbacks, and forming a continuous plain under surface throughout the transverse extent of the arch, a hopper, and bolts secured between adjacent keyed blocks and securing the hopper to the arch.

In testimony whereof I affix my signature in presence of two witnesses.

PAUL L. CROWE.
